DESIGN FOR A BROILER

Foster L. Talge, Kansas City, Mo.

Application March 19, 1938, Serial No. 75,975

Term of patent 7 years

To all whom it may concern:

Be it known that I, Foster L. Talge, residing at Kansas City, in the county of Jackson and State of Missouri, have invented a new, original, and ornamental Design for a Broiler of which the following is a specification, reference being had to the accompanying drawing forming part thereof, in which

Fig. 1 is a perspective view of a broiler showing my new design.

Fig. 2 is a top plan view of the broiler shown in Fig. 1.

Fig. 3 is a side elevation of the broiler shown in Fig. 1.

Fig. 4 is an end elevation of the broiler shown in Fig. 1.

I claim:

The ornamental design for a broiler, substantially as shown.

FOSTER L. TALGE.
